CLAIM

We claim the ornamental design for a blade, as shown and
described.

DESCRIPTION

FIG. 1 is a top perspective view of a blade showing our new
design;

FIG. 2 is a bottom perspective view thereof;

FIG. 3 is a right side view thereof, wherein the left side view
is a mirror image thereof;

FIG. 4 is a front view thereof, wherein the rear view is a
mirror image thereof.

FIG. 5 is a top view thereof; and,

FIG. 6 is a bottom view thereof.

The ornamental design which is claimed is shown in solid
lines in the drawings.

The broken lines in the drawings illustrate portions of the
blade and form no part of the claimed design. The dot-dash-
dot broken lines in the drawings define the bounds of the
claim and form no part thereof.
